No. 12,655

Jan. 3, 1882

UNITED STATES PATENT OFFICE.

ISAAC P. TURNER, OF TROY, NEW YORK, ASSIGNOR OF ONE-HALF TO
JOHN H. COLBY, OF SAME PLACE.

DESIGN FOR INTERIOR FORM OF CUFF-BOX.

SPECIFICATION forming part of Design No. 12,655, dated January 3, 1882.

Application filed November 18, 1881. Term of patent 7 years.

To all whom it may concern:

Be it known that I, ISAAC P. TURNER, of the city of Troy, county of Rensselaer, and State of New York, have invented a Design of a New and Useful Form for the Interior of a Cuff-Box, and of which, taken in connection with the annexed photograph, the following is a specification.

My invention relates to the internal form and configuration of that portion of a cuff-box which is exposed to view when the cover is removed to show the cuffs or to take them from the box.

My invention of a design consists, as shown in the annexed photograph, of the combined horizontal and vertical form of the two inclosures A and B, which are rectilinear horizontally, and their tops have their end walls beveled, so that one of the sides of each inclosure is higher than the other, and the ends of each inclosure are beveled off oppositely to the ends of the other, so that the higher side of each inclosure will be upon the same side of the box as the lower side of the other.

The letters C' C' designate the end walls of the inclosure A, and C²C² the end walls of the inclosure B.

D' designates the highest side of the inclosure A and D² its lower side, and E' the higher

side of the inclosure B and E² its lower side, 30 the relative form of these oppositely-placed bevels and the location of them with reference to each other producing the configuration and form of the top of the cuff interior.

I am well aware that cuff-boxes have been 35 made that were cut angularly inwardly and downwardly toward the center of the box from the ends, with the lower boundary of each inclosure in contact at the center of the box.

Having thus described my invention, what 40 I claim, and desire to secure by Letters Patent, is—

The design for the form and configuration of a cuff-box interior, consisting of the two rectilinear inclosures A and B, each having sloping 45 ends, so as to make one side of each inclosure higher than the other, and the two inclosures arranged with reference to each other to form the box interior, so that the higher side of one inclosure and the lower side of the other shall 50 be upon each and the same side of the box, as shown and described.

Signed at Troy, New York, this 10th day of November, 1881.

ISAAC P. TURNER.
